M. Theodore Simmons

UNITED STATES PATENT OFFICE

ARTHUR WILLIAM NAUS, OF NEW YORK, N. Y.

DESIGN FOR A BUCKLE

Application filed March 9, 1931. Serial No. 39,011. Term of patent 14 years.

To all whom it may concern:

Be it known that, I, ARTHUR WILLIAM NAUS, a citizen of the United States, residing at New York, in the county of New York, and State of New York, have invented a new, original, and ornamental Design for Buckles, of which the following is a specification, reference being had to the accompanying drawings, forming part thereof.

The buckle is intended to be used upon straps, belts, garters, slippers, hats, and the like. It comprises two halves assembled together, each half carrying a jewel and joined thereto an ornamental mounting frame for the jewel of the opposite half.

Figure 1 is a plan view of one half of my new buckle showing a jewel at the left hand side, and an ornamental mounting frame at

the right hand side, the two joined by a connecting throat.

Figure 2 is a plan view of the other half of my new buckle with the jewel carried at the right hand side and an ornamental mounting frame at the left hand side, the two being joined together by a connecting throat.

Figure 3 is a plan view of the buckle with the halves of Figures 1 and 2 assembled together, the respective jewels being located in their respective mounting frames, showing my complete new buckle.

Figure 4 is a side elevation of the assembled buckle of Figure 3.

I claim:

The ornamental design for a buckle as shown and described.

ARTHUR WILLIAM NAUS.
